SHOE REPAIR MACHINE UNIT

George McElveen Wynn, Atlanta, Ga., assignor to
The Auto-Soler Company, a corporation of
Georgia

Application January 26, 1949, Serial No. 507

Term of patent 14 years

(Cl. D9—2)

To all whom it may concern:

Be it known that I, George McElveen Wynn, a citizen of the United States, residing at Atlanta, in the county of Fulton and State of Georgia, have invented a new, original, and ornamental Design for a Shoe Repair Machine Unit, of which the following is a specification, reference being had to the accompanying drawing, forming part thereof, and in which the single figure is a perspective view of a shoe repair machine unit show-

ing my new design. The side and back of the shoe repair machine unit not shown in the drawing are substantially plain.

I claim:

The original design for a shoe repair machine unit, substantially as shown and described.

GEORGE McELVEEN WYNN.
